Primary Examiner — Darlington Ly(74) *Attorney, Agent, or Firm* — Birch, Stewart, Kolasch & Birch, LLP(57) **CLAIM**

The ornamental design for a control panel for combination domestic detection device, as shown and described.

DESCRIPTION1. Control panel for combination domestic detection device
1.1 is a front perspective view of a control panel for combination domestic detection device showing our new design;**1.2** is a front elevation view thereof;**1.3** is a rear elevation view thereof;**1.4** is a left side elevation view thereof;**1.5** is a right side elevation view thereof;**1.6** is a top plan view thereof;**1.7** is a bottom plan view thereof; and**1.8** is an exploded front perspective view thereof.

The even broken lines in the reproductions illustrate portions of the control panel for combination domestic detection device that form no part of the claimed design.
